APPARATUS FOR PUMPING

Kenneth C. D. Hickman, Rochester, N.Y., assignor to Consolidated Electrodynamics Corporation, Pasadena, Calif., a corporation of California

Application February 16, 1956, Serial No. 565,811

3 Claims. (Cl. 183—2)

This invention relates to improvements in fan-type pumps or blowers used to pump gases or vapors.

Fan-type pumps are generally divided into two main classes, namely, centrifugal fans and axial-flow fans. The centrifugal fans use rotating impellers to drive the pumped gas or vapor by centrifugal force in a direction radial to that of the impeller axis of rotation, while the axial-flow fans use propellers to drive the pumped material in a direction along the propeller axis of rotation. For the purpose of describing this invention, the terms "vapor" and "gas" are used interchangeably, and the term "fan" is used to include both centrifugal and propeller fans. Both types of fans have long been used for transporting vapors or gases under relatively low pressure differentials. However, one of the disadvantages of these fans in pumping vapors or gases of relatively low average density or average molecular weight is that the force that can be developed by the rotation of the fan impeller on the gas molecules is small, and therefore the pressures that can be produced are relatively low.

This invention provides apparatus for enabling fans to pump a gas of a given average molecular weight to a pressure head greater than can ordinarily be produced by conventional fans of comparable size and operating at the same speed of rotation. The operation of fans designed for pumping gases or vapors of a given average molecular weight is improved by "vapor loading" the fans, that is, introducing into the fan inlet a vapor having a molecular weight greater than that of the gas or vapor being pumped. The fan imparts more momentum to the molecules of heavier vapor than it imparts to the molecules of the lighter vapor, and the heavy molecules entrain the lighter molecules to provide a more effective pumping action than can be achieved on the light molecules alone. This improvement permits fans to produce vacuua comparable to those produced by vapor-operated vacuum pumps, such as the well known oil ejector pumps.

In terms of apparatus the invention contemplates a vapor pump comprising a casing having an inlet and an outlet. A rotatable impeller is mounted in the casing for forcing vapor from the inlet to the outlet, and means are provided for introducing a relatively high molecular weight vapor into the pump on the inlet side of the impeller. In a preferred form, means are also provided for condensing some vapor on the outlet side of the impeller and returning at least a portion of the condensed vapor to the inlet side of the impeller.

The invention contemplates pumping a first vapor constituent of a given average molecular weight with a fan having an outlet and an inlet. The first vapor constituent is admitted into the fan inlet and a second vapor constituent of a greater molecular weight than that of the first is also introduced into the fan inlet so that the mixture of the vapor constituents is pumped to the fan outlet at a pressure greater than would be produced if the fan were pumping only the first vapor constituent.

This invention also includes the feature of achieving with a fan fractional separation of a vapor having a

2

plurality of constituents of different vapor pressures, along with improved pumping by the fan of the light vapor constituents. For example, a fan used in a still in accordance with this invention to pump and fractionate a vapor having various constituents of different vapor pressures is operated to compress the vapor to a pressure sufficient to condense at least the less volatile constituents from the vapor. All of the condensed constituents may either be removed from the pump as a product, or else 10 in part be recirculated through the fan to improve the efficiency of the fan in pumping the lighter and more volatile constituents in the vapor.

Use of the fan of this invention in a still to obtain fractional separation of a vapor of various constituents provides some important advantages over conventional stills. One advantage is that it permits the purification of high molecular weight, low volatility compounds at a low pressure and low temperature, and reduces the tendency for such compounds to decompose as when separated 15 in conventional stills at higher pressures and temperatures. Another advantage is that the fan used in a still provides a "negative pressure drop," that is, the pressure in the still increases in the direction of vapor flow rather than decreases as occurs in conventional stills. As applied to 20 the petroleum industry, for instance, molecular high vacuum distillation with the fan of this invention is obtained at the low pressure end of the still, while relatively high pressure separation is secured at the other end of this still. Moreover, because of the internal pumping action of the fan, such operation is achieved at a 25 high throughput with low thermal hazard. This permits commercial separation not heretofore possible for the high boiling, high molecular weight constituents of petroleum.

The invention will be more completely understood from the following detailed description, taken in conjunction with the accompanying drawings, in which:

Fig. 1 is a sectional elevation of a fan made in accordance with the present invention and using both the axial-flow and centrifugal flow principles.

Fig. 2 is a vertical section taken on line 2—2, partially broken away, showing a centrifugal impeller and an associated stator deflector; and

Fig. 3 is a graph of data showing how the vapor loading principle of this invention improves the operation of a fan.

Referring to the drawings, the vapor loaded pump comprises a horizontal, generally cylindrical casing 10 secured at its righthand end (as viewed in Fig. 1) by means of bolts 12 to an end plate 14. An annular gasket 16 disposed in an annular groove 18 in the end plate, effects a gas-tight seal between the casing and the end plate. The casing is integrally formed in three sections of stepped diameters, increasing from left to right (as viewed in Fig. 1), the smallest being a discharge section 20, which forms the outlet end of the casing, the intermediate size being an intermediate section 21, and the largest being an inlet section 22, which forms the inlet end of the casing. An inwardly extending lip 23 is formed integrally at the inlet end of the casing. An inlet spider 24 mounted in the inlet end of the casing by means of radially extending inlet guide vanes 25 supports a ball bearing 26 in the center of the casing-inlet, and an outlet spider 28 mounted in the outlet end of the casing supports a second ball bearing 30 in the center of the outlet end of the casing.

A shaft 32 rotatably sealed by a packing gasket 34 extends through an outwardly projecting boss 36 on the outside surface of the end plate, and also extends coaxially through the casing to be journaled in each of the ball bearings. The shaft is adapted to be connected to a motor (not shown) and rotated in a counterclockwise direction as viewed in Fig. 2.

An axial flow compressor stage is mounted in the inlet section of the pump casing and is of the type described in the text book entitled "Internal Combustion Engines Analysis and Practice," second edition, by Edward F. Obert, published by International Textbook Company of Scranton, Pennsylvania. Two longitudinally spaced rotor plates 37 are secured to the shaft by keys 38 on the outlet side of the inlet spider. A hub ring 39 is rigidly attached between the two rotor plates at their peripheries, and a hub cap 40 is rigidly attached to the periphery of the downstream rotor plate on the side of the plate nearer the pump outlet. A plurality of outwardly extending rotor blades or propellers 41 are rigidly attached to the periphery of each rotor plate and extend almost to the interior of the inlet section. A plurality of stator vanes 42 are attached to the interior of the inlet section to extend inwardly on the downstream side of each set of rotor blades. The stator vanes terminate adjacent the hub ring or the periphery of the hub cap. The rotor blades and stator vanes are set in the conventional manner at opposite angles to the longitudinal axis of the pump casing so that vapor may be forced from the pump inlet toward the outlet with an accompanying increase in pressure.

In the intermediate section of the pump casing, a plurality of disc rotors 43 are rigidly attached, welded for example, to the shaft and extend perpendicular thereto almost to the casing. Each rotor is provided with a plurality of radially extending vanes or impellers 44, mounted on the inlet side of each rotor and extending from the periphery of each rotor to an intermediate location thereon.

A plurality of annular stator plates 46 are attached at their outer peripheries to the casing interior at spaced intervals and extend radially between adjacent rotors. Each stator plate is provided on its inlet side with a plurality of perpendicularly extending diffusers 47. Each diffuser extends from the outer periphery to the inner periphery of its respective stator plate and is curved to present a concave surface to the gas or vapor being discharged from the preceding rotor so that the gas is deflected in toward the center of the following rotor.

Rotors, impellers, stators and diffusers are similarly mounted in the outlet section of the pump casing, and are assigned the same reference characters as indicated for the intermediate section of the pump. A final stator plate 48 with its associated diffusers 49 is mounted within in the outlet section of the casing on the outlet side of the final rotor and adjacent the inlet side of the outlet spider.

A separate deflecting and spacing spool 50 having a concave surface around its periphery is rigidly attached, as by welding, to the shaft between adjacent rotors to aid in deflecting the pumped gases in the direction as indicated by the arrows in Fig. 1.

A separate liquid receptacle 51 is formed in the bottom of the casing between each of the stator plates, and each stator plate is provided with an opening 52 at its lower edge and between two diffusers so that there is a communication between the successive receptacles of the pump to permit liquid to flow therebetween as described more fully below. The lip at the inlet end of the casing and the shoulder formed between the inlet and intermediate sections of the casing form the receptacle nearest the casing inlet. The outlet spider and the end stator plate 48 form the receptacle nearest the casing outlet, the outlet spider and stator plate 48 both having openings 52 to permit liquid to flow from the receptacle at the outlet toward the pump inlet.

A bell jar housing 53 is disposed around the pump casing and secured at its open end to the end plate by means of bolts 54. An annular gasket 55 in an annular groove 56 in the end plate effects a gas-tight seal between the housing and the end plate. A separate withdrawal tap 57 is sealed through the housing and connected to

each respective receptacle within the casing. A separate valve 58 in each withdrawal tap exterior of the housing permits liquid to be withdrawn or added to the individual receptacles as desired.

An inlet conduit 59 in the end of the bell jar housing remote from the end plate is adapted to be connected to either a source of vapor or a system to be evacuated. An outlet conduit 60 in the portion of the end plate within the pump casing extends through a cold trap 61 where it is connected to an upwardly extending discharge line 62. A downwardly extending condensate return conduit 63 is connected to the lower portion of the outlet conduit 60 within the cold trap so that vapors, which may be condensed in the cold trap, may be returned through a vapor loading line 64, to which the lower end of condensate return conduit 63 is connected, to an intermediate point in the pump casing. A valve 65 in condensate return conduit 63 is used to control the return of condensate from the cold trap.

A reservoir 66, containing a vapor loading liquid 67 is connected by a supply line 68 to the vapor loading line 64, and a valve 69 in the supply line controls the admission of the vapor loading liquid into the vapor loading line 64. The vapor loading material may be introduced at any point within the pump casing, however, when using the pump to produce a vacuum, it is often advantageous to admit the material to one of the intermediate impellers, and operate the impellers nearest the casing inlet substantially "dry" to produce a vacuum which is virtually free of the vapor loading material, a condition which is not practical with conventional vacuum pumps using the vapors of a boiling liquid to produce a vacuum. For example, the opening in the stator plate nearest the casing inlet may be plugged so that no liquid flows into the receptacle nearest the casing inlet. With this arrangement the propellers (axial-flow stages) and the rotor nearest the casing inlet are not directly vapor loaded, and by their pumping action prevent the backstreaming of vapor loading material into the volume being evacuated.

An upright cooling coil 70 having an inlet 71 and an outlet 72 sealed through the end plate is disposed adjacent the outlet side of the last stator plate. A first pressure gauge 74 is connected through the end plate to the annular space between the housing and the pump casing to measure pressure at the inlet end of the pump. A second pressure gauge 76 is connected through the end plate to measure pressure at the outlet end of the pump.

In the operation of the vapor loaded pump shown in Figs. 1 and 2 to pump a relatively light gas such as air (which has an average molecular weight of 29), the shaft is rotated counterclockwise as viewed in Fig. 2 at a suitable speed (say 5000 r.p.m.) causing the air to be forced from the inlet to the outlet in the direction shown by the arrows. The decrease in the cross-section area of the pump casing from the inlet to the outlet accommodates the decrease in volume of the air as it is compressed.

As the pumping proceeds, the vapor loading liquid, which is preferably of a molecular weight of at least several times the average molecular weight of air, is admitted from the reservoir into the vapor loading line 64 where it is then delivered into the pump casing interior. The fluid fills the receptacle into which it is introduced and flows through the openings in the stator plates toward the inlet end of the pump casing due to the pressure difference between the various stages within the pump. Eventually, the liquid reaches a stage which is of a sufficiently low pressure that the liquid either boils or at least volatilizes at a substantial rate. The heavy vapor loading molecules are then picked up by the impellers either the propeller or centrifugal type, and pumped toward the pump outlet, entraining the lighter air molecules. Due to the greater mass of the vapor loading molecules, higher pressures are developed in each

stage than would be possible if the relatively light air molecules were pumped alone. As the heavy molecules move toward the pump outlet into stages of increasing pressure, they are condensed into the receptacles and flow back toward the pump inlet where they are again vaporized. The cooling coil and the cold trap at the pump outlet are operated at properly selected temperatures to prevent any undue loss of the vapor loading material.

The vapor loading material may either be a single compound, or it may be a mixture of compounds having constituents of various vapor pressures. If the latter is used, the various constituents automatically fractionate within the pump, that is, the less volatile constituents find an equilibrium position in the low pressure or inlet end of the pump and are cyclically evaporated from one receptacle, condensed in a succeeding receptacle, and returned to a preceding receptacle. The more volatile constituents behave in a like manner in stages of higher pressure.

The pump shown in Figs. 1 through 2 may be used in numerous different ways. For example, the pump is well adapted for rapidly evacuating a large volume of gas or vapor, and may be operated either against atmospheric pressure or be provided with a mechanical backing pump at the outlet end.

The curves of Fig. 3 illustrate the effect of vapor loading a pump of the type shown in Figs. 1 and 2, in which a mechanical backing pump was connected to the discharge line 62 at the outlet end of the pump. A cyclic ether having a molecular weight of 416 and a vapor pressure of 31 millimeters of mercury at 25° C. (sold under the trade name of Fluorochemical O-75) was used as the vapor loading material. The mechanical pump was operated at a constant speed and a flow rate meter was connected to the inlet conduit 59 so that a variable and measurable amount of air was admitted to the pump inlet.

Curve A of Fig. 3 shows how the pressure varied at the pump inlet as air was permitted to leak into inlet conduit of the housing at various rates, the pump shaft being stationary, and no vapor loading material being introduced into the pump. Curve B of Fig. 3 shows how the pressure varied at the pump inlet with various air leak rates while the pump shaft was rotated at 6400 r.p.m. The difference between curves A and B shows the capacity of the pump at 6400 r.p.m. when it was not vapor loaded. Curve C shows how the pressure varied at the pump inlet with leak rate, the vapor loading material being introduced into the pump casing, but the pump shaft being stationary. Curve C shows that the vapor pressure of the vapor loading material with the pump shaft stationary caused the pressure at the pump inlet to be slightly greater than when the vapor loading material is not present. Curve D shows the pumping capacity of the pump when the pump was operated vapor loaded with the shaft turning at 5800 r.p.m. Curve D demonstrates that vapor loading increased the pumping capacity of the pump by several fold, even though the pump was operated at a slower speed (5800 r.p.m. vapor loaded, as compared to 6400 r.p.m. not vapor loaded).

Although the vapor loading material used in the example given above was a chemically pure compound, the invention is not limited to the use of vapor loading materials of a single constituent with a single vapor pressure. In fact, it is preferable to use a material having fractions of several vapor pressures, the constituents making up the vapor loading material being selected to fit the pressure range in which the vapor loaded pump is to be operated. An advantage of the vapor loaded pump is that even if the vapor loading material is made up of constituents of different vapor pressures, and is introduced in the inlet end of the pump, the various fractions of the vapor loading material will automatically seek an equilibrium position. For example, as the mixture of

constituents is driven from the pump inlet to the outlet, entraining lighter vapors as it is so driven, the less volatile constituents soon reach a pressure range within the pump where at least a portion of them condense and fill the proximate receptacle. The slightly more volatile constituents are condensed as they reach zones of higher pressures within the pump, until eventually each receptacle contains condensed constituents, the volatility of the condensed constituents increasing from the pump inlet to the pump outlet. The condensed fluids flow through the openings in the stators toward the pump inlet until they reach a stage of sufficiently low pressure where they are again volatilized and vapor load the pump. The noncondensables or constituents which are not readily condensed by the pressures and temperatures encountered within the pump, are discharged from the pump outlet, and are either condensed by the cooling coil or the cold trap, or are discharged through conduit 60.

It is the inherent fractionating property of the pump of this invention which makes it well suited to serve in a fractionating still. For example, the inlet of the pump is adapted to be connected to a source of vapor having constituents of various vapor pressures, say a boiler containing a mixture of liquid petroleum hydrocarbons.

The pump is operated to reduce the pressure on the liquid hydrocarbons to a point where boiling or substantial evaporation occurs. The more volatile and lower molecular weight constituents are removed first by the pump, and are either condensed in the outlet stage of the pump, or are pumped out of the discharge line. As pumping proceeds, increasing amounts of the lower boiling and higher molecular weight constituents are evaporated from the hydrocarbon liquid mixture by the pump and pumped therethrough. The higher molecular weight constituents serve to drive the lower molecular weight compounds to effect an efficient pumping action on the lower molecular weight constituents. The higher molecular weight constituents are condensed in the various receptacles within the pump, the order of deposition from the pump inlet to the outlet being in the inverse order of the volatility of the constituents. The condensed constituents reflux from receptacle to receptacle until an approximately equilibrium composition is reached in each receptacle. The liquid product in each receptacle is then separately removed from the pump by means of the withdrawal taps.

This type of fractionation is ideal for separating and purifying low boiling, high molecular weight compounds which are ordinarily not recoverable since they are usually decomposed by the pressures and temperatures encountered in conventional still operations. The reason for the improved separation resulting in a fan-type still is that the pressure in the still increases in the direction of the flow of the vapor within the still, permitting molecular high vacuum evaporation of the low boiling constituents at the still inlet, and relatively high pressure separation of the more volatile and less easily damaged constituents at the pump outlet.

I claim:

1. Apparatus for fractionally separating a vapor having constituents of different vapor pressures, the apparatus comprising a casing having an inlet and an outlet, a plurality of rotatable impellers serially disposed in the casing for progressively increasing pressure in the casing from the inlet toward the outlet to cause vapor constituents to condense in the casing in accordance with their vapor pressures, and means for transferring condensed vapor from one point at one pressure in the casing to another point in the casing at a lower pressure.
2. Apparatus for fractionally separating low boiling, high molecular weight liquids having constituents of different vapor pressures comprising a casing having a plurality of pumping stages arranged intermediate an inlet and an outlet with said pumping stages disposed for progressively increasing pressure from the inlet toward

the outlet, means for introducing a low boiling, high molecular weight liquid having constituents of different vapor pressures into said casing adjacent said outlet, said casing being defined to allow the liquid to be fractionated to flow toward said inlet to thereby allow each of said constituents to vaporize at a different pumping stage whereby the vapors are pumped to a stage of a higher pressure to cause the constituents of the liquid to condense from the inlet to the outlet in inverse order of their vapor pressures, and means for withdrawing the 10 condensed constituents from the pumping stages.

3. Pumping apparatus for pumping gases of low molecular weight comprising a casing having an inlet and an outlet with pumping stages of increasing pressure arranged intermediate said inlet and outlet, rotatable 15 impellers arranged in said casing for pumping a low molecular weight gas from said inlet to said outlet, a source of a high molecular weight liquid having constituents of various vapor pressures, means for introducing said liquid adjacent said outlet of said casing, said casing being defined to allow said liquid to flow through said pumping stages towards said inlet while the various constituents of said liquid vaporize in the various pump-

5

ing stages, the resulting vapors mixing with the gas to be pumped and entraining same into a pumping stage of higher pressure, said vapors being pumped towards said outlet until a pumping stage is reached that causes the condensation of the vapors whereby the compression of the apparatus acting on the low molecular weight gas is increased.
